UNITED STATES PATENT OFFICE.

WALDEMAR KOPS, OF NEW YORK, N. Y., ASSIGNOR TO NEMO CIRCLET COMPANY, INC.,
A CORPORATION OF NEW YORK.

BRASSIÈRE.

Application filed February 21, 1923. Serial No. 620,343.

To all whom it may concern:

Be it known that I, WALDEMAR Kops, a citizen of the United States, residing in the borough of Manhattan, city, county, and 5 State of New York, have invented an Improvement in Brassières, of which the following is a specification.

This invention relates to a brassière, and like other garments of its general type is 10 adapted to be secured on the body of the wearer to overlie, confine and support the busts. In brassières as generally constructed, the tension applied at the front of the garment produces a more or less flat front 15 effect. Obviously the flattening of the busts in front causes a greater or less spread of the flesh at the sides, and the object of my invention is the provision of a garment in which the flat front effect will be produced 20 and adequate support provided for the spread of the flesh at the sides of the wearer, and also in the same garment to provide tension straps which are so placed as to be adapted to bear against and support and 25 thus control the diaphragm of the wearer.

In carrying out the present invention, therefore, I employ a brassière adapted to extend around the body of the wearer and to be preferably connected at the front, the 30 front sections of the garment being constructed of a plurality of parts preferably tapered downwardly so as to terminate in tension straps by which simultaneously a straight downward and laterally downward 35 tensions are produced in the front portions of the garment to exert corresponding pressures against the underlying portions of the body of the wearer thereby effecting the straight front appearance and making 40 provision for the adequate support of the spread of the flesh at the sides of the body. The garment also includes suitable tension straps underlying the lower portions of the front members of the garment as hereinbefore 45 described to exert a predetermined pressure against the diaphragm of the wearer to support and control the same, all of which will be hereinafter more particularly described.

50 In the drawing:

Fig. 1 is a perspective view illustrating the garment made in accordance with my present invention.

Fig. 2 is a plan showing the inner side of

the garment with the parts thereof in a flattened position.

Fig. 3 is a front elevation of the outer side of the front of the garment, and

Fig. 4 is a section on line 4—4, Fig. 3.

Referring to the drawing, it will be seen 60 that the garment made in accordance therewith comprises a body member adapted to extend around the body of the wearer and to be secured in position thereon preferably at the front and that the front portions of 65 the garment are similarly constructed with the parts thereof, however, lying in oppositely disposed positions. In the right hand side of the garment there is a front section 10 provided along the edge thereof with a 70 reinforcing strip 11 to which a series of hooks 12 is suitably secured. The front portion of the garment also includes sections 75 designated by 13, 14 and 15 which are preferably tapered to conform to the body and to cause the tension applied to the same to exert the required pressure against the body. The section 13 is secured to the front section 10 along a line of stitching 16, while the section 14 is secured to the section 13 80 along the line of stitching 17 and the section 15 is secured to the section 14 along a line of stitching 18. The forward edge of the section 13 extends from the top of the garment to a point indicated at 19 which 85 is appreciably above the lower edge of the garment, and the opposite edge of the section 15 extends from the top of the garment to a point indicated at 20 which is also appreciably above the lower edge of the garment. The lower portions of the sections 90 13, 14 and 15 terminate in a strap 21 which reaches below the lower edge of the garment and has attached thereto a hose supporter strap indicated at 22.

The back of the garment preferably includes a central section 23 and back sections 24 and 25, the back section 24 being connected to the front section 15 along a line of stitching 26 which is preferably the 100 axial line of the garment, while the section 23 is connected to the section 24 along a line of stitching 27 and to the section 25 along the line of stitching indicated at 28.

In the lower front portion of the garment 105 preferably underlying the lower portions of the sections 13, 14 and 15 I employ a tension strap comprising an inelastic section 30 and

elastic sections 31 and 32, these sections being connected along the line indicated at 33. The rearward edge of the section 30 is secured to the back section 24 by the same line of stitching 26 which connects the section 15 thereto, and the lower edge of this section of the tension strap together with the lower edge of the elastic section 31 complete the continuity of the lower edge 10 of the garment, whereas a portion of the elastic section 32 overlies a part of the elastic section 31 and the upper edge of the elastic section 32 completes the continuity of the upper edge of the tension strap. It will 15 be noted that the elastic sections 31 and 32 being placed at divergent angles to one another will permit of a combined circumferential and downwardly extending tension being exerted by the strap to cause corresponding pressure against the diaphragm or 20 underlying portion of the body of the wearer. Furthermore, as the upper portion of the tension strap at the rearward end thereof underlies a part of the section 15, and as 25 the greater portion of the tension strap underlies the lower portions of the sections 13, 14 and 15, the function of the tension strap will be assisted by the action of the overlying portions of the front sections of the 30 garment.

Similarly the other side of the garment comprises a front section 34 having a reinforcing strip 35 secured to the edge thereof and provided with a series of eyes 36 connected thereto in any desired manner and corresponding in number with the hooks 12. The front portion of the garment at this side comprises sections 37, 38 and 39 corresponding respectively with the sections 13, 14 and 15. The section 37 is connected to the front section 10 along a line of stitching 40, while the section 38 is connected to the section 37 along a line of stitching 41, and the section 39 is connected to the section 38 along the line of stitching 42, the section 39 being connected to the back section 25 along a line of stitching 29 which is the other axillar portion of the garment. At its forward edge the section 37 45 extends from the upper edge of the garment to a point indicated at 43 which is an appreciable distance above the lower edge of the garment, and as in the other half of the garment the rearward edge of the section 39 extends from the upper edge of the garment to a point indicated at 44 which is also appreciably above the lower edge of the garment. The lower portions of the section 37, 38 and 39 taper to form a strap 45 corresponding to the strap 21 and to which is connected a suitable hose supporter 46.

In this side of the garment the inelastic portion of the tension strap is indicated at 47 and the elastic sections thereof at 48 and 49, these sections being connected along the

line indicated at 50. In the lower front edge of the garment there is suitably attached a depending tape 51 provided with a hook 52 adapted to engage a corset steel or an attachment provided on an under-garment for this purpose in order to maintain the lower edge of the brassière in position that is to prevent the same from creeping upwardly on the body of the wearer and also as indicated in the drawing the garment may be provided with suitable shoulder straps 53 and 54 which in some instances include yielding or elastic insert sections 55 and 56.

It will now be understood that in the garment as hereinbefore described provision has been made for exerting a downward tension in the front portion of the garment to produce a corresponding inward pressure on the body of the wearer to obtain a flattening front effect. Provision has also been made for exerting laterally extending downward tensions producing corresponding lateral pressures in the side portions of the garment which are transmitted to the body of the wearer to provide for the support of the flesh as spread because of the flattening effect. Provision has also been made to exert a variable pressure on the diaphragm to control and assist in supporting the same. All these devices are so associated as to coact with each other in producing the desired results. It will furthermore be understood that while the garment as herein shown and described is adapted to be connected at the front the same may be otherwise constructed to carry out the purposes of the invention without departing from the nature and spirit thereof.

I claim as my invention:

1. In a brassière having the lower edge thereof adapted to conform approximately with the waistline of the wearer, front sections, means for connecting the said front sections, tension straps extending circumferentially from the front sections to approximately the axillar lines of the garment, with the lower edge of each tension strap completing the continuity of the lower edge of the brassière, front and side members, parts of which overlie portions of the said tension straps, and a member depending from each of the said front and side members and through which downward tension is applied to the said front and side members causing the same to coact with the said tension straps in supporting and confining the diaphragm and busts of the wearer.

2. In a brassière having the lower edge thereof adapted to conform approximately with the waistline of the wearer, front sections, means for connecting the adjacent edges of the front sections, tension straps each comprising an elastic and an inelastic

section extending from the front sections to the axillar lines of the garment, with the lower edge of each tension strap completing the continuity of the lower edge of the garment, and front and side members each comprising a plurality of sections converging downwardly overlying a portion of the tension straps and terminating appreciably below the same whereby through tension applied to the said front and side members the same coact with the tension straps to confine and support the diaphragm and busts of the wearer.

3. In a brassière having the lower edge thereof adapted to conform approximately with the waistline of the wearer, front sections, means for connecting the adjacent edges of the front sections, tension straps each comprising an inelastic and elastic sections, the elastic sections diverging and being connected to the front section, the in-

elastic sections being connected to the garment at substantially the axillar line thereof and the lower edge of each tension strap continuing and completing the continuity 25 of the lower edge of the garment, front and side members each comprising a plurality of downwardly converging sections terminating in a strap extending below the lower edge of the tension straps, and hose supporters attached to the lower ends of the said converging sections of the front and side members whereby the lower portions of the said front and side members overlie parts of the tension straps and coact with 35 the said tension straps in confining and supporting the diaphragm and busts of the wearer.

Signed by me this 26th day of January, 1923.

WALDEMAR KOPS.
